(57) **CLAIM**

The ornamental design for a wall section, as shown and described.

DESCRIPTION

FIG. 1 is a perspective view of a wall section according to the new design.

FIG. 2 is a left-side view of the wall section of FIG. 1.

FIG. 3 is a right-side view of the wall section of FIG. 1.

FIG. 4 is a rear view of the wall section of FIG. 1.

FIG. 5 is a front view of the wall section of FIG. 1.

FIG. 6 is a top view of the wall section of FIG. 1; and,

FIG. 7 is a bottom view of the wall section of FIG. 1.

The drawings contain symbolic break lines. The portions of the article between the break lines forms no part of the claimed design. The characteristic feature of the design resides in the wave pattern formed by the top surface of the wall.
